UNITED STATES PATENT OFFICE

2,493,893

TOILET PAPER ROLL HOLDER

Stephen J. Miller, Tampa, Fla., assignor to
Gus G. Harris, Chicago, Ill.

Application July 28, 1947, Serial No. 764,190

12 Claims. (Cl. 242—55.2)

1

My invention relates to improvements in toilet paper roll holders, and particularly to a roll holder intended and adapted to be installed and used in public rest rooms and lounges, in rest rooms of railway and airplane and bus terminals, in the rest rooms of amusement places and hotels and restaurants and taverns and like establishments, and in any and all places where many and various and passing members of the public are apt to use the rest room.

An object of my invention is to provide a device of this character which is of simple and inexpensive type to thus be made and sold at prices substantially within the scale of other present and less efficient devices, and which is of such construction that when installed and in use a toilet paper roll will be mounted and held in place and will be positively locked and retained in place against accidental or casual or intentionally deliberate removal.

Another purpose is to provide a holder of this character which is of durable and lasting construction, and with which the holder can not ordinarily be removed or displaced from the wall or other mounting, and the parts thereof can not be broken by the use of the human hands and without the use of tools or other heavy instrumentalities, either while the paper roll is in place, or after the roll has been used or exhausted and the parts of the holder are exposed.

Still another purpose is to so construct the holder that a locking or key bar can be inserted in place after a roll of paper is placed on the holder, and then the parts can be manipulated to positively lock the bar in roll retaining position with the locking parts contained within the central opening of the roll and thus inaccessible until the roll of paper has been used or exhausted, following which the parts of the locking mechanism are exposed for manual release of the roll retaining key or bar locking means.

Yet another purpose is to provide a chain or other flexible member which, when the holder is in use, is disposed obliquely or angularly along one side of the roll of paper, so that on each revolution of the roll of paper the strip of paper may be torn across, the parts and construction being such that the roll can not be bodily removed and the paper may not be unreeled in long lengths.

Still another purpose is to so employ the chain or flexible member that it serves two purposes, namely, to cut or tear the paper when a roll of paper is in place and is being unreeled, and to

2

retain the key or locking bar when the holder is empty.

Still another purpose is to so construct the holder that it has a sturdy and durable means of mounting upon a wall or other supporting structure, and the entire structure is sturdy and durable in the inherent parts to thus defy breaking or removal by the use of the human hands; and which accomplishes a great saving of paper as a roll can not be removed as an entirety and the paper can not be unreeled from the roll in long lengths.

With the above and other objects in view, some of which will be apparent to those skilled in the art, and others of which are inherent in the construction and mounting and use of the parts, my invention includes certain novel features of construction and combinations and arrangements of structural parts and features which will be hereinafter set forth and described in connection with the drawings, and then pointed out in the claims.

In the drawings:

Fig. 1 is a view in perspective of a holder made according to my invention and with the locking key or bar in the position it will occupy when the holder is not in use.

Fig. 2 is a perspective view of the holder with a roll of paper in place.

Fig. 3 is a composite perspective view with the parts separated and strung out somewhat in the order of their assembly placement.

Fig. 4 is a view in side elevation showing a holder constructed according to my invention as it will appear when mounted upon a wall or other supporting structure, and with the holder in the unlocked position and ready for reception of a roll of paper.

Fig. 5 is a sectional view taken substantially on line 5—5 of Fig. 4.

Fig. 6 is a view similar to Fig. 4 looking down upon the parts as they are disclosed.

Fig. 7 is a detailed sectional view substantially on line 7—7 of Fig. 6.

Fig. 8 is a longitudinal sectional view through the parts as disclosed in Fig. 6.

Fig. 9 is a view similar to Fig. 8 showing the parts in the position assumed when a roll of paper is in place and is locked upon the holder.

Fig. 10 is a transverse sectional view, substantially on line 10—10 of Fig. 9.

Fig. 11 is a top plan view showing another embodiment of my invention.

Fig. 12 is a longitudinal sectional view at right angles through the disclosure of Fig. 11 with the parts in unlocked relation.

Fig. 13 is a view similar to Fig. 12 with the parts moved to the locked position.

Fig. 14 is a top plan view disclosing still another modified embodiment of the invention.

Fig. 15 is a longitudinal sectional view at right angles through the showing of Fig. 14 with the parts in unlocked position.

Fig. 16 is a view like Fig. 15, with the parts in locked position.

In the first disclosed embodiment of my invention, a mounting or base plate 1 has fastening receiving openings 2 in the ends thereof adapted to receive screws 3, or lag screws or other fastenings, by which the holder is secured in place on a wall or other mounting member or structure 4. In the present instance, the mounting or base plate 1 is disclosed as being substantially elongated, but it will be obvious that this plate can be of any desired shape or configuration. A shank 5 extends inwardly from the mounting or base plate 1, and a bearing spindle 6 extends outwardly from the outer face of the mounting or base plate 1, substantially at right angles. The shank 5 and spindle 6 can be made as a single cylindrical bar inserted through and welded in an opening in the mounting or base plate 1, or these parts can be made or assembled in any other suitable and desired manner. As disclosed in Fig. 4 of the drawings, an opening 7 is drilled, bored, or otherwise formed in the wall 4, and the shank 5 is inserted in this opening so that the mounting or base plate 1 is disposed against the face of the wall, the screws or other fastenings 3 being inserted through the openings 2 to thus mount the parts with the bearing spindle 6 extending substantially horizontally outwardly from the wall. A roll-supporting or carrying member 8, perhaps best shown in Fig. 3 of the drawings, is made up of strap metal or other suitable sheet material, with the side bar portions 9 and 10 extending from a middle crossbar portion 11, and with its extremities 12 and 13 bent inwardly in overlapping relation. The extremity 12 of the member 8 has an opening therethrough to revolvably receive the spindle 6, and the extremity 13 has a registering opening 14 of slightly elongated shape also adapted to receive the spindle 6, while the middle or crossbar portion 11 is provided with a bearing opening 15 substantially aligned with the openings in the extremities 12 and 13, and adapted to revolvably receive the outer end of the bearing spindle 6. The middle or crossbar portion 11 of the roll supporting or carrying member 8 has the outer edges thereof cut away or bent in or otherwise formed to reduce the width of this portion intermediate the side bars 9 and 10, as indicated at 16. The side bar portion 9 has a stop 17 extending inwardly therefrom, and this stop may be made or applied in any desired manner. In the present instance, I have illustrated the stop 17 as being a portion of the side bar member 9 which is cut along three sides and is then turned inwardly substantially at right angles. The side bar portion 10 is provided with a latch pawl 18, which pawl has its detent face toward the extremity 13, and while this pawl can be made or applied in any desired manner, I have found it convenient to cut on three sides of a portion of the metal of the side bar 10, and to bend this tab inwardly at an acute angle, thus providing an inclined outer face over which a locking portion can ride to pass and catch over the detent end of the latch pawl.

A locking member 19, also preferably made of

a piece of strap metal, or other suitable material, is bent to substantially rectangular form with the side bar portions 20 and 21 extending in substantially parallel relation from the middle crossbar portion 22, and with the extremities 23 and 24 turned inwardly in overlapping relation. These overlapped extremities have openings 25 aligned therethrough and adapted to slidably and rotatably receive the bearing spindle 6. The locking member 19 has the side bar portions 20 and 21 of such width and the crossbar portion 22 of such dimensions that when this member is assembled with the roll supporting or carrying member 8, the extremities 23 and 24 of the locking member 19 can be sprung apart and over the crossbar portion 11 of the member 8, and the side bar portions 20 and 21 will fit and slide within the reduced or recessed portion at 16. In assembling the parts, the extremities 23 and 24 of the locking member 19 are located on the inner side of the stop 17, and in such relation that as the locking member 19 is moved inwardly by pressure exerted upon the middle or crossbar portion 22, the extremities 23 and 24 will ride over the inclined face of pawl 18 and will be in position to be engaged against return movement by the abutting face of this locking or latch pawl 18. Since the side bar portion 10 of the roll-supporting member 8 is more or less flexible and resilient, this side bar portion will normally resiliently move out to a slightly angular position, as illustrated in Fig. 3, which movement is accommodated by the elongation of the opening 14, and the latch or locking pawl 18 will thus be normally resiliently held in a position where it will not engage with the inturned extremities 23 and 24 of the locking member 19. However, as will be hereinafter more fully described, when a roll of paper is placed upon the roll-supporting or carrying member 8, the usual cardboard cylinder serving as a center for the ordinary roll of toilet paper will press the side bar 10 inwardly to a position where the pawl 18 will engage with the inturned ends of the locking member 19.

A paper roll confining crossbar member 26, preferably of a length somewhat approximating the diameter of the usual roll of paper, has a bearing opening 27 through the middle portion thereof. This crossbar 26 is of a width and shape to be fitted between the side bars 9 and 10 of the roll-supporting or carrying member 8, with the bearing opening 27 thereof aligned with opening 14 to receive the spindle 6, and with the ends extending substantially radially.

In assembling the parts, the end of bearing spindle 6 is inserted through the aligned openings of the overlapping extremities 12 and 13 of the substantially rectangular roll-supporting or carrying member 8, and then through the opening 27 of the crossbar member 26, this crossbar member being located between the side bar portions 9 and 10 of the member 8 and extending substantially radially on opposite sides of the spindle, in position to serve as an inner stop for a roll of paper when fitted in place upon the holder. A bearing collar or sleeve 28 is then placed upon the bearing spindle 6, and the spindle is then moved endwise through registering openings 25 of the overlapped extremities 23 and 24 of the locking member 19, which member 19 is assembled with the roll-supporting or carrying member 8, and the parts are then shoved on to the bearing spindle 6 so that the end of this spindle is received through bearing opening 15 in the crossbar portion 11 of the roll-supporting

member 8. Following such assembly, the bearing collar or sleeve 28 is moved inwardly upon the bearing spindle 6 to a position where this bearing collar or sleeve will hold the parts in the desired position and rotatably upon the bearing spindle 6. The bearing collar or sleeve 28 is then welded, pinned, or otherwise secured in fixed position upon the bearing spindle 6 so that the assembled parts are held against endwise movement and displacement and are yet free to revolve or rotate or turn around and upon the spindle 6. With the parts assembled and secured in the manner as described, a very sturdy and durable toilet paper roll receiving and supporting structure is provided, and the structure is such that there is little likelihood or possibility of a person being able to remove or damage any of the parts by the use of the hands alone, and without employment of tools or other heavy instrumentalities.

With the parts assembled in the manner set forth, the inherent resiliency or flexibility of the side bar 10 causes this bar to swing angularly outwardly, within the limits of the elongated opening 14, so that the locking or latch pawl 18 is laterally displaced out of position to engage with and lock the locking member 19. Thus, the locking member 19 has free and unobstructed endwise movement in both directions within the limits defined by the outer face of the collar or sleeve 28 and the inner face of the stop 17. In its outermost position, the locking member 19 has an axial extent somewhat greater than the length of the usual and standard roll of paper, and thus as the roll of paper, as indicated at 29 in Fig. 2, is fitted endwise over and upon the roll-supporting or carrying member 8, the looped outer portion of the locking member 19 will extend considerably beyond the end of the roll. The transverse dimensions of the roll-supporting or carrying member 8 are such that as the roll of paper is fitted in place with the opening and tubular supporting central portion 30 as usually provided in such paper rolls is moved endwise on to the supporting or carrying member 8, the side bar portion 10 will be moved in to bring the latch pawl 18 into locking position, and at the same time there will be frictional engagement between the roll and the member 8 so that as the roll is turned, this member 8 will rotate upon the spindle 6 and will cause rotation of the parts assembled therewith.

A locking key or bar 31, which is conveniently made of substantially the same length as the crossbar member 26, has a transverse width somewhat greater than the distance between the inner faces of the side bar portions 20 and 21 of the locking member 19, on the inner side of the middle crossbar portion 22 thereof. The locking key or bar 31 is notched or cut away on its side edges in the middle portion, as at 32 and 33, and this locking key or bar is so made that when the locking member 19 is pulled out to the position shown in Fig. 1, and a roll of paper is in place upon the holder, the locking key or bar 31 can be turned obliquely or angularly and can have one end thereof inserted through the opening between the side bar portions 20 and 21, and then the key can be twisted so that the middle portion thereof lies adjacent to the inner side of the middle crossbar portion of locking member 19, and the side bar portions 20 and 21 of this locking member will then be received in the notched or cut-away openings 32 and 33.

With the parts in the relation as described,

pressure exerted upon the outer end or crossbar portion 22 will cause the locking member 19 to be moved inwardly to bring the locking key or bar 31 into such close proximity to the outer end of the roll of paper that this member can not be again twisted angularly or obliquely for withdrawal of the locking key or bar. As the locking member 19 is shoved inwardly to the locking position, the inturned extremities 23 and 24 will ride over the inclined inner face of the latch pawl 18, and will be presented in position to be retained in the locking position, and against outward movement, by the abutment face of the latch pawl 18.

As the locking portions are entirely within the opening and the tubular supporting member 30, no one can have access to release the parts while the roll of paper is in place. When the paper has been used, the tubular supporting portion 30 can be torn or cut away and the locking parts are then released so that locking member 19 can be again pulled out to give sufficient clearance for tilting or twisting the locking key or bar 31 to a position where it can be removed and withdrawn endwise to permit placement of another roll of paper.

Since there is possibility that the locking key or bar 31 might be removed by a person other than an authorized attendant desiring to place a new roll of paper, I provide a flexible member, such as chain 34, or a cable or other suitable member not readily broken or damaged, and I connect this chain or flexible member at one end, as at 35, to one end of the crossbar member 26, the other end of the chain or flexible member 34 being connected, as at 36, to one end of the locking key or bar 31. The chain or flexible member 34 is made sufficiently long to extend substantially obliquely across the outer portion of the roll of paper, as illustrated in Fig. 2 of the drawings, when the locking key or bar 31 is in the locked roll-retaining position, and when the locking key or bar is removed from this position, the chain or flexible member 34 serves to suspend and tether the locking key or bar and to guard against loss or unauthorized removal thereof.

As the bars 26 and 31 extend radially substantially at right angles, the chain or flexible member 34 extends across the outer side of the roll substantially obliquely with respect to the axis of rotation, and since the chain or flexible member is more or less loose on the surface of the roll, a person may readily grasp the end of the strip of paper and unreel the same; however, upon each complete revolution of the roll the chain or flexible member 34 will cause the paper to tear off at the usual lines of perforation, or at the line of the chain or flexible member, and consequently it will not be possible for anyone to pull off or unreel a great length of paper. Thus, it will be seen that with my improved structure a considerable saving in paper will result, since when a roll of paper is locked in place it is impossible for anyone to remove the roll as an entirety; since the locking means can be released only when the complete roll has been exhausted; and, at the same time no one can unreel any considerable length of paper since the chain or flexible member 34 will cause severance of the paper transversely on each revolution of the roll.

With the modified embodiment of my invention as illustrated in Figs. 11, 12 and 13, the functions and results accomplished are substantially the

same, the chief difference being in the construction and association of parts. In this modified construction, the roll-supporting and carrying member 37 is of substantially U-shaped form, with its ends outturned as at 38, and secured upon the cross-bar 39 by welding, riveting, or in any other suitable manner. Locking bars 40 and 41 are welded or otherwise secured across between the side bars of the roll-supporting and carrying member 37, preferably adjacent to but spaced from the crossbar 39, so that these locking bars are in the zone which will be embraced within and covered by a roll of paper. Locking member 42 is made substantially U-shaped and has its ends outturned as at 43 and 44 to thus provide locking flanges. In the unlocked position of the parts, these locking flanges 43 and 44 are adapted to be engaged with the inner sides of the transverse locking bars 40 and 41, by springing the arms of the locking member 42 inwardly and then moving this member longitudinally outwardly, and a stop is provided at 45 on the locking member to limit outward endwise movement of this locking member so that the locking flanges 43 and 44 will never be pulled outwardly beyond the outer edges of the transverse locking bars 40 and 41. The remaining portions of the structure and mounting are substantially the same as hereinbefore described in detail with the first disclosed embodiment of my invention, and it will be seen that a locking key or bar can be inserted through the opening of the looped outer end of the locking member 42 after a roll of paper has been fitted in place, and then inward pressure upon the locking member 42 will cause the locking flanges 43 and 44 to ride forwardly over the inner faces of the transverse locking bars 40 and 41 and to spring out into the locking position. When the roll of paper has been used, the resilient arm of the locking member 42 can be pressed inwardly and the locking flanges 43 and 44 are then disengaged so that this locking member 42 can be pulled endwise outwardly to a position to allow removal of the locking key or bar.

With the modified form of the invention illustrated in Figs. 14, 15, and 16, the roll-supporting member 46 can be substantially the same as described in connection with the showing in Figs. 11, 12 and 13, with the exception that the roll-supporting member 46 has only a single transverse locking bar 47. Locking member 48 is substantially U-shaped in general configuration, and this locking member has one end thereof in-turned, as at 49, the inturned end 49 being provided with an opening 50 slidably receiving the bearing spindle and retaining the locking member in position and yet permitting endwise movement thereof. The opposite end of the locking member 48 is turned out in the provision of the locking flange 51 adapted to spring out and engage behind the inner edge of the transverse bar 47 when the locking member is in locked position, a stop 52 being provided to limit outward movement of the locking member 48, after the manner of stop 45.

From the foregoing, it will be seen that I have provided a toilet paper roll holder of simple and inexpensive construction so sturdy and durable that it will not be likely to be displaced from its mounting or be dismembered or dismantled or damaged except by such force as may require the employment of tools or other heavy instrumentalities; and, that the device is of such construction that its use will result in economy of

paper since it is impossible to remove a roll of paper as an entirety from the holder, and it is impossible to unroll or withdraw long lengths of paper.

While I have herein shown and described only certain specific embodiments of my invention, and have suggested only certain other possible adaptations, it will be appreciated that many changes and variations can be made in the form, construction, arrangement and assembly of the parts, without departing from the spirit and scope of my invention.

I claim:

1. A toilet paper roll holder comprising an outstanding spindle, means to mount said spindle on a wall, a supporting member rotatable on said spindle and adapted to receive a roll of paper, a cross-bar removably associated and rotatable with the supporting member and engageable with the outer end of the roll, and internal locking means holding said cross-bar in roll retaining and locking position.

2. A toilet paper roll holder comprising a spindle, means to mount said spindle on a wall, a supporting member rotatable on said spindle and adapted to receive a roll of paper, a cross-bar carried at the inner end of the spindle, a locking member endwise movable with respect to the supporting member, a cross-bar interfit-table with the locking member adjacent to the outer end of a roll of paper on said supporting member, and inter-engaging means on the supporting member and the locking member within the limits of space occupied by a roll of paper and adapted to lock the parts against release when the locking member is moved inwardly to dispose the cross-bar associated therewith adjacent to the outer end of a roll of paper.

3. A toilet paper roll holder comprising a spindle, means to mount said spindle on a wall, a supporting member rotatable on said spindle and adapted to receive a roll of paper, a cross-bar carried at the inner end of the spindle, a locking member endwise movable with respect to the supporting member, a cross-bar interfit-table with the locking member adjacent to the outer end of a roll of paper on said supporting member, and a flexible member connected with one end of the first-mentioned cross-bar and one end of the locking bar and thus disposed across the outer side of the roll of paper from one end to the other.

4. A toilet paper roll holder comprising a spindle, means to mount said spindle on a wall, a supporting member rotatable on said spindle and adapted to receive a roll of paper, a cross-bar carried at the inner end of the spindle, a locking member endwise movable with respect to the supporting member, a cross-bar interfit-table with the locking member adjacent to the outer end of a roll of paper on said supporting member, inter-engaging means on the supporting member and the locking member within the limits of space occupied by a roll of paper and adapted to lock the parts against release when the locking member is moved inwardly to dispose the cross-bar associated therewith adjacent to the outer end of a roll of paper, the cross-bar at the inner end of the roll and the cross-bar at the outer end of the roll being disposed to extend substantially laterally and radially at substantially an angle of 90 degrees apart, and a flexible member connected between an end of the cross-bar and an end of the cross-bar locking member and thus

disposed substantially obliquely adjacent to the outside of the roll of paper.

5. A toilet paper roll holder comprising a mounting spindle, means to secure said spindle upon a supporting portion, a paper roll receiving means revolvable on said spindle, and a flexible member carried by the means on the spindle and extending substantially across the outer side of the roll from one end to the other and locked against removal.

6. A toilet paper roll holder comprising a mounting spindle, means to secure said spindle upon a supporting portion, a paper roll receiving means revolvable on said spindle, and a flexible member carried by the means on the spindle and extending substantially obliquely across the outer side of the roll.

7. A toilet paper roll holder comprising a mounting plate having a shank extending from one side and a bearing spindle portion extending from the other side, a looped roll supporting member rotatably mounted on the spindle, a cross-bar extending transversely at the inner end of said looped member to serve as a stop for a roll of paper placed endwise on said looped member, a second looped member also carried by the spindle and the first looped member and endwise movable with respect thereto, a cross-bar insertable transversely through the outer portion of the second looped member to prevent removal of a roll of paper placed upon the first looped member, and internal locking means engageable between the first and second looped members when said second looped member is moved inwardly, whereby said second looped member and the cross-bar associated therewith are held in an assembled and locked relation.

8. A toilet paper roll holder comprising a mounting plate having a shank extending from one side and a bearing spindle portion extending from the other side, a roll supporting member constituting an elongated strap-like portion having a substantially rectangular form with its extremities overlapped at one end and being provided with openings in the overlapped extremities receiving the mounting spindle, a cross-bar disposed at the inner end of the rectangular member and extending laterally on opposite sides of and adjacent to the inner end of the spindle, a second substantially rectangular member having its ends overlapped at one end and provided with openings receiving the spindle loosely whereby the second member is endwise movable with respect to the roll supporting member, means coacting between the rectangular members limiting outward movement of the second member, a cross-bar removably fitted within the loop of the outer end of the second member, and means interengaging between the two members when the second member is moved inwardly to dispose the cross-bar thereof adjacent to the end of a roll of paper fitted on the first member, whereby the parts are locked to retain a roll of paper against displacement and removal.

9. A toilet paper roll holder comprising a mounting plate having a shank extending from one side and a bearing spindle portion extending from the other side, a roll supporting member constituting an elongated strap-like portion having a substantially rectangular form with its extremities overlapped at one end and being provided with openings in the overlapped extremities receiving the mounting spindle, a cross-bar disposed through the rectangular member and extending laterally on opposite sides of and adja-

cent to the inner end of the spindle, a second substantially rectangular member having its ends overlapped at one end and provided with openings receiving the spindle loosely whereby the second member is endwise movable with respect to the roll supporting member, means coacting between the rectangular members limiting outward movement of the second member, a cross-bar removably fitted within the loop of the outer end of the second member, means interengaging between the two members when the second member is moved inwardly to dispose the cross-bar thereof adjacent to the end of a roll of paper fitted on the first member, whereby the parts are locked to retain a roll of paper against displacement and removal, the cross-bar at the inner end of the roll and the locking bar at the other end of the roll being disposed to extend laterally at substantially an angle of 90 degrees apart, and a flexible member connected between an end of the cross-bar and an end of the locking bar and thus disposed substantially obliquely around the outside of a roll of paper.

10. A toilet paper roll holder comprising a spindle, means to mount said spindle on a wall, a roll mounting member rotatable on said spindle, a cross-bar on said spindle at the inner end of the roll mounting member limiting inward movement of a roll of paper, a substantially U-shaped locking member endwise movably mounted on said roll mounting member and presenting a looped cross-bar portion at its outer end, a locking key bar having its middle portion of reduced width insertable through the looped end of the locking member when the locking key or bar is disposed diagonally and adapted to receive the side portions of the locking member to retain the key in place when the key is fitted with the reduced portion thereof in substantially a parallel plane with respect to the looped end of the locking member, and interfitting locking and detent portions on the parts of the roll mounting member and the locking member retaining the locking member in inward disposition when the locking member having the locking key or cross-bar therein is moved inwardly.

11. A toilet paper roll holder comprising a spindle, means to mount said spindle on a wall, a roll mounting member rotatable on said spindle, a cross-bar on said spindle at the inner end of the roll mounting member limiting inward movement of a roll of paper, a substantially U-shaped locking member endwise movably mounted on said roll mounting member and presenting a looped cross-bar portion at its outer end, a locking key bar having its middle portion of reduced width insertable through the looped end of the locking member when the locking key or bar is disposed diagonally and adapted to receive the side portions of the locking member to retain the key in place when the key is fitted with the reduced portion thereof in substantially a parallel plane with respect to the looped end of the locking member, interfitting locking and detent portions on the parts of the roll mounting member and the locking member retaining the locking member in inward disposition when the locking member having the locking key or cross-bar therein is moved inwardly, and a flexible member such as a chain connected at one end of the cross-bar and at one end of the locking key or bar to thus be disposed substantially transversely across the outer side of a roll of paper as mounted upon the holder, and serving to tether and prevent

loss of the locking key or bar when in the released position.

12. A toilet paper roll holder comprising a spindle, means to mount said spindle on a wall, a roll mounting member rotatable on said spindle, a cross-bar on said spindle at the inner end of the roll mounting member limiting inward movement of a roll of paper, a substantially U-shaped locking member endwise movably mounted on said roll mounting member and presenting a 15 looped cross-bar portion at its outer end, a locking key bar having its middle portion of reduced width insertable through the looped end of the locking member when the locking key or bar is disposed diagonally and adapted to receive the side portions of the locking member to retain the key in place when the key is fitted with the reduced portion thereof in substantially a parallel plane with respect to the looped end of the locking member, interfitting locking and detent portions on the parts of the roll mounting member and the locking member retaining the locking member in inward disposition when the lock-

ing member having the locking key or cross-bar therein is moved inwardly, the cross-bar at the inner end of the roll and the locking key or bar at the other end of the roll being disposed to extend laterally and radially at substantially an angle of 90 degrees apart, and a flexible member connected between an end of the cross-bar and an end of the locking bar and thus disposed substantially obliquely along the outside of the roll.

10. of paper.

STEPHEN J. MILLER.
